UNITED STATES PATENT OFFICE.

JAMES CROMPTON AND WILLIAM GALLAGHER, OF SALFORD, MANCHESTER, ENGLAND.

BOILER AND LIKE FURNACE.

Application filed August 14, 1922. Serial No. 581,814.

To all whom it may concern:

Be it known that JAMES CROMPTON and WILLIAM GALLAGHER, both subjects of the King of Great Britain and Ireland, residing at Salford, Manchester, England, have invented new and useful Improvements in or Relating to Boiler and like Furnaces, of which the following is a specification.

This invention relates to boiler and the like furnaces of the channel type wherein air is forced through a plurality of channels located below the fire bars and from which the air is forced through openings regularly disposed over the entire area of the grate, the different channels communicating with different sets of openings whereby the supply of air to each set of openings is independent of all the other sets.

The main object of the present invention is to provide a furnace, of the kind referred to, adapted for use either with a forced draft or a natural draft, a further object being to provide an improved construction and arrangement of grate for such furnaces.

According to the invention, the fire bars proper are of T-shape in cross section or of flat, plate-like or other formation adapted to be mounted on supporting bars or the like arranged with the broad side vertically disposed so that adjacent bars constitute two sides of the desired channels. Said supporting members may be arranged longitudinally of the furnace and the fire bars proper disposed thereon transversely of the same. The undersides of the channels are provided with closure plates hingedly or otherwise mounted thereon so as to be capable of being moved into position to complete the channels or moved to allow of a natural draft over the entire grate area.

The invention will be more particularly described by the aid of the accompanying drawings in which:

Fig. 1 is a longitudinal section of the furnace of a Lancashire boiler showing the invention applied.

Fig. 2 is a sectional plan view of Fig. 1 with part of the fire bars removed.

Fig. 3 is a front view of the furnace shown in Fig. 1.

Fig. 4 a transverse sectional view.

Fig. 5 is a detail sectional view showing the flaps closed, drawn to an enlarged scale, and

Fig. 6 is a plan view of Fig. 5.

In carrying the invention into effect according to one convenient manner as illustrated, a furnace *a* is provided with fire-bars *b* transversely of the furnace. The fire-bars *b* are supported on longitudinally arranged bars *c* mounted on the cross stays *d*, *e* at the front and back respectively, with the broad sides vertically disposed so that adjacent bars constitute two sides of the desired channels *f*. The fire bars *b* are formed with projections *b*¹ on one side and are vertical on the other side so as to form regularly disposed openings *b*² for the passage of air to the fire.

Hingedly mounted transversely of the furnace *a* and on the underside of the bars *c* are a number of comparatively narrow slats *g* or closure members adapted, when turned against the bottom edge of the bars *c* to complete the channels *f* with adjacent bars, but when turned downwards to allow of the unobstructed passage of air from the ash-pit to the fire bars *b*. The slats *g* are hinged to the outside bars *c* as clearly seen in Figs. 2 and 4.

Said slats or closure members are manipulated by suitable mechanism which may conveniently comprise a rod *h* extending from the back to the front of the furnace, inclined planes *i* and *j* being provided at said back and front respectively to coact with the rod so that by moving the latter backwards or forward by means of a suitable manipulating handle *h*¹ on the projecting end, or other means, the closure members *g* may be raised to complete the channels or lowered to give access to the same for cleaning purposes or to allow of a natural draft taking place. The bar *h* is provided with anti-friction rollers and the edges of each closure member *g* contacting with the bar *h* are preferably provided with an anti-friction roller *g*¹ as shown. Some or all of the channels *f* register with openings *k* through which, by injectors or other means, a current of air is forced into said channels. The closure members *g* are preferably comparatively narrow, say 3 inches wide, so as not to impede the passage of the natural draft but they may be of any desired width, and when arranged longitudinally of the fire bars may each be adapted to close one or more channels and instead of being hing-

edly mounted may be slidably mounted. The usual steam injectors or other means are provided for creating the forced draft.

What we claim is:—

5. 1. Furnaces for boilers, and the like, comprising flat bars set on edge and arranged longitudinally of the furnace at a distance apart such as to produce a series of longitudinal channels, fire-bars transversely arranged 10 ranged across and upon the said channel bars, closure members hinged below the channels and transversely arranged relatively thereto, and a single sliding bar and complemental inclined planes whereby all the closure members can be simultaneously 15 operated, substantially as described.
2. Furnaces for boilers, and the like, comprising flat bars set on edge and arranged longitudinally of the furnace at a distance 20 apart such as to produce a series of longitudinal channels, fire-bars transversely arranged across and upon the said channel bars, closure members hinged below the channels and transversely arranged relatively 25 thereto, an anti-friction roller on the edge of each closure member to engage a sliding bar, a sliding bar having anti-friction rollers to engage inclined planes and inclined planes arranged to receive the sliding bar, whereby 30 all the closure members are simultaneously opened or closed, substantially as described.
3. Furnaces for boilers, and the like, com-

prising flat bars set on edge and arranged longitudinally of the furnace at a distance 35 apart such as to produce a series of longitudinal channels, means to force air into the channels, fire-bars transversely arranged across and upon the said channel bars, closure members hinged below the channels 40 and transversely arranged relatively thereto, and a single sliding bar and complemental inclined planes whereby all the closure members can be simultaneously operated, substantially as described.

4. Furnaces for boilers, and the like, comprising flat bars set on edge and arranged longitudinally of the furnace at a distance apart such as to produce a series of longitudinal channels, means to force air into the channels, fire-bars transversely arranged across and upon the said channel bars, closure members hinged below the channels and transversely arranged relatively thereto, an anti-friction roller on the edge of each 55 closure member to engage a sliding bar, a sliding bar having anti-friction rollers to engage inclined planes and inclined planes arranged to receive the sliding bar, whereby all the closure members are simultaneously 60 opened or closed, substantially as described.

In testimony whereof we have signed our names to this specification.

JAMES CROMPTON.
WILLIAM GALLAGHER.
